UNITED STATES PATENT OFFICE.

PERLEY L. KIMBALL, OF BELLOW'S FALLS, VERMONT, ASSIGNOR TO VERMONT FARM MACHINE COMPANY, OF BELLOW'S FALLS, VERMONT, A CORPORATION OF VERMONT.

CENTRIFUGAL SEPARATOR.

SPECIFICATION forming part of Letters Patent No. 712,310, dated October 28, 1902.

Application filed May 29, 1902. Serial No. 109,456. (No model.)

To all whom it may concern:

Be it known that I, PERLEY L. KIMBALL, a citizen of the United States of America, residing at Bellows Falls, in the county of Windham and State of Vermont, have invented 5 certain new and useful Improvements in Centrifugal Separators, of which the following is a specification.

The object of my invention is to provide a 10 device of the class specified having features of novelty and advantage.

Figure 1 is a view in side elevation of a 15 separator-bowl, partly broken away to show construction. Fig. 2 is a sectional plan view on the line $x^2 x^3$ of Fig. 1. Fig. 3 is a sectional perspective view of the interior of the bowl. Fig. 4 is a sectional plan view on the line $x^4 x^4$ of Fig. 1.

In the drawings, A denotes the separator- 20 bowl.

B B denote the escape-passages for the skim-milk through the bottom of the separator-bowl.

C denotes an annular projection or ring on 25 the interior wall of the bowl at or near the bottom thereof.

D D are vertical mortises through this ring, one side of the mortises preferably being formed by the interior wall of the bowl.

30 E E denote lateral openings or outlets with which the vertical mortises D D communicate. These lateral openings preferably are flared, so that they can be easily cleaned. Extending upward from this annular projection or ring are tapering webs F F, which 35 act as guides to direct the liner G to its proper position. The liner is adapted to fit inside of the annular projection or ring and is held above the bottom of the bowl by a 40 spacing device, as the boss K. As shown in the drawings this boss is secured to the bottom of the liner; but it may be equally well secured to the bottom of the bowl. On the bottom of the liner there are also located 45 wings M N.

As the blue milk is separated from the cream it moves outwardly to the wall of the bowl and then down, passing through the mortises and the outlets into the space be- 50 tween the bottom of the liner and the floor

of the bowl. The wings on the bottom of the liner keep this blue milk moving and cause it to flow out through the escape-passages B B. Heretofore tubes have been secured to the floor of the bowl, extending 55 from its walls over the skim-milk-escape tubes; but it has been found that uncleanly persons would not properly cleanse these tubes and in some extreme cases even allow them to become clogged. To overcome 60 these objections, I have devised the bowl herein shown and described, which performs the work required of it with extreme thoroughness and is readily cleaned and kept in 65 a sweet and pure condition.

I claim as my invention—

1. In combination; a separator-bowl; a projection from the interior wall of the bowl and located near the floor thereof; the liner; and a spacing device between the liner and the 70 floor of the bowl, substantially as described and for the purposes set forth.

2. In combination; a separator-bowl; the annular projection from the interior wall of the bowl and located near the floor thereof; 75 communicating vertical and lateral flow-openings through said projection; the liner having its lower end located within said projection and above the lateral flow-openings; and a spacing device between the liner and the 80 floor of the bowl, substantially as described and for the purposes set forth.

3. In combination; a separator-bowl; an annular projection from the interior wall of the bowl and located near the floor thereof; slant-faced guides appurtenant to said projection; liner; and a spacing device between the liner and the floor of the bowl, substantially as described. 85

4. In combination; a separator-bowl; an annular projection from the interior wall of the bowl and located near the floor thereof; slant-faced guides appurtenant to said projections; and a liner carrying a supporting-boss underneath, substantially as described and for the 90 purposes set forth.

5. In combination; a separator-bowl having escape-conduits for the blue milk through its floor; a liner carrying downwardly-projecting wings on its lower end; an annular 95

projection from the interior wall of the bowl having vertical mortises communicating laterally with the space between the liner and the floor of the bowl, substantially as described.

- 5 6. In combination; a separator-bowl having escape-conduits for the blue milk through its floor; a liner carrying downwardly-projecting wings on its lower end; an annular
10 projection from the interior wall of the bowl having vertical mortises communicating lat-

erally by flare-mouthed openings with the space between the bottom of the liner and the floor of the bowl, substantially as described and for the purposes set forth.

15

In testimony whereof I affix my signature in presence of two witnesses.

PERLEY L. KIMBALL.
